A. L. EMENS

INDUCTION ELECTRICITY METER

Original Filed March 12, 1926

35 Inventor:
Albert L. Emens
By G. A. Bragg Atty.

UNITED STATES PATENT OFFICE.

ALBERT L. EMENS, OF LA FAYETTE, INDIANA, ASSIGNOR TO DUNCAN ELECTRIC MANUFACTURING COMPANY, OF LA FAYETTE, INDIANA, A CORPORATION OF ILLINOIS.

INDUCTION ELECTRICITY METER.

Application filed March 12, 1926, Serial No. 94,239. Renewed October 14, 1927.

My invention relates to an induction electricity meter employing a supporting base having a forwardly projecting wall to constitute said base, a chamber in which the current and pressure electromagnets are disposed, a spindle rotatably supported upon said base in front of said magnets, and a metallic disc in inductive relation to said magnets.

One feature of my invention also relates to an induction electricity meter employing a terminal chamber connected with and extending outwardly from the aforesaid wall and provided with a lid having means for holding it in closed position. Such a meter of the prior art was provided with a cover seated upon the front portion of the forwardly projecting wall of the base and serving to enclose the spindle, the damping magnet system, the counting train, and the spindle carrying the metallic disc or armature, these parts being located in front of the current and pressure electromagnets of the meter. It was possible for a person desiring to prevent the operation of such a meter for the purpose of obtaining current without cost to insert a strip of steel between the cover and its seat to an extent to engage the armature disc to prevent its rotation. In accordance with my invention, I add a cover which covers the main cover of the meter, this added cover extending rearwardly beyond the front of the forwardly projecting base wall, which it surrounds, to an extent which will prevent the insertion of such a strip into engagement with the armature disc. In the preferred embodiment of the invention, two rods are carried by the base, these rods projecting forwardly through the added cover and having nuts threaded thereon which press upon the inner cover to hold it in place and other nuts, also threaded upon said rods, and pressing upon the added cover to hold it in place.

In accordance with another characteristic of my invention, the cover which I supply is formed with an opening receiving the terminal chamber, the lid fastening means being enclosed by this cover to guard it from unwarranted access.

I will explain my invention more fully by reference to the accompanying drawing in which Fig. 1 is a front view, with parts broken away, illustrating a meter equipped in accordance with my invention; Fig. 2 is

a sectional view on line 2—2 of Fig. 1; and Fig. 3 is a sectional view, on a larger scale, on line 3—3 of Fig. 1.

The meter base is inclusive of a plate 1 formed with a forwardly projecting wall 2 to constitute a chamber, the base having a perforated ear 3 extending from the top thereof for receiving a mounting screw 4 which is passed through the ear into the wall 5 or other support. Other screws 6 are passed through the lower portion of the base into the support 5. The base is usually formed of iron and the chamber defined thereby is commonly closed by an iron wall 7 which is suitably joined to and within said projecting wall 2. The potential electromagnet 8 and the current electromagnet 9 are anchored to and upon the rear of the wall 7 by means of screws 10 passing through the cores of the electromagnets into the wall 7, there being distance preserving sleeves 11 surrounding the screws and interposed between the magnet cores and said wall. The electromagnets are upon the rear side of the wall 7, being surrounded by the wall 2 and enclosed within the chamber defined by the wall 2. The upright meter spindle 12 is positioned by the bearings 13 and 14 which are carried by the wall 7 upon the front thereof. The spindle carries a non-magnetic metallic armature disc 15 which extends through an opening 16 in the wall 7 and into the space between the poles of the magnets to be in inductive relation thereto. The spindle is provided with a worm 17 in mesh with the initial wheel 18 of a gear train which operates the indicators of the meter, in a manner well known. This gear train is supported by a permanent magnet 19 and this magnet in turn is held by the clips 20 which are carried by and project forwardly from the wall 7. A main cover 21, commonly of glass, is seated upon the front portion of the wall 2, a sealing gasket 22 being interposed between the cover and said wall. The terminal chamber 23 is connected with and extends downwardly or outwardly from said wall 2, in accordance with common practice, this terminal chamber carrying the terminals for the electromagnets with which terminals the circuit wires 24 are also connected.

The terminal chamber is provided with a lid 25 which is hinged or pivoted at 26. A fastening screw 27 is passed through the

lid into the body of the terminal chamber to hold the lid in a closed position. The lid is provided with a perforated ear 28 to receive a sealing wire 29 which is also passed through a perforation formed in the screw whereby the lid is sealed. The added cover 30, of my invention, is desirably also formed of glass, this cover covering the first cover and all of the parts of the meter which have been described excepting the terminal chamber which is received within a U-shaped opening 31 that is formed in the base portion of the added cover, this opening, by virtue of its U-shape, permitting the added cover to be slipped into place and over the terminal chamber after the meter proper has been mounted upon the support 5. The fastening screw 27 that holds the lid 25 closed and the ear 28 that is carried by the lid, together with the sealing wire 29 are also covered by the second cover 30 so as to further guard the lid from being unwarrantably opened. The two covers are held in position by two rods 32 which are carried by the base and project forwardly therefrom through the covers. Two nuts 33 are threaded upon these rods and press upon the inner cover 21 to hold it upon its seat. Two other nuts, preferably in the form of wing nuts 34, are screwed upon the outer ends of the rods and press upon the second cover 30 to hold the base thereof against the wall or other support 5. Sealing wires 35 are passed through the rods and in front of the wing nuts to prevent these nuts and the covers from being removed.

In addition to further protecting the fastening means which hold the terminal chamber lid closed, the second cover, by extending rearwardly beyond the seat for the first cover, guards against the insertion of a metal strip into holding engagement with the armature disc whereby the meter is prevented from being fraudulently placed in inoperative condition.

Having thus described my invention, I claim:

1. In an induction electricity meter, the combination with a supporting base having a forwardly projecting wall to constitute said base a chamber; of a terminal chamber connected with and extending outwardly from said wall and provided with a lid; fastening means for holding said lid in closed

position; current and pressure electromagnets disposed within the first chamber; a spindle rotatably supported upon said base in front of said magnets; a metallic disc upon said spindle and in inductive relation to said magnets; a cover seated upon the front portion of the aforesaid wall; and a second cover covering the first cover and surrounding said forwardly projecting wall, the second cover extending rearwardly beyond the place of engagement of the first cover with said forwardly projecting wall and being formed with an opening receiving said terminal chamber, the second cover also covering the fastening for the terminal chamber lid. 70

2. In an induction electricity meter, the combination with a supporting base having a forwardly projecting wall to constitute said base a chamber; of a terminal chamber connected with and extending outwardly from said wall; current and pressure electromagnets disposed within the first chamber; a spindle rotatably supported upon said base in front of said magnets; a metallic disc upon said spindle and in inductive relation to said magnets; a cover seated upon the front portion of the aforesaid wall; and a second cover covering the first cover and surrounding said forwardly projecting wall, the second cover extending rearwardly beyond the place of engagement of the first cover with said forwardly projecting wall and being formed with an opening receiving said terminal chamber. 85

3. In an induction electricity meter, the combination with a supporting base having a forwardly projecting wall to constitute said base a chamber; of current and pressure electromagnets disposed within the chamber; a spindle rotatably supported upon said base in front of said magnets; a metallic disc upon said spindle and in inductive relation to said magnets; a cover seated upon the front portion of the aforesaid wall; and a second cover covering the first cover and surrounding said projecting wall and extending rearwardly beyond the place of engagement of the first cover with said forwardly projecting wall. 100

In witness whereof, I hereunto subscribe my name.

ALBERT L. EMENS.
